UNITED STATES PATENT OFFICE.

WILLIAM H. THOMPSON, OF MEMPHIS, TENNESSEE, ASSIGNOR TO THOMPSON ELECTRIC CLOCK COMPANY, OF MEMPHIS, TENNESSEE, A CORPORATION OF TENNESSEE.

ELECTRIC AUTOMOBILE-CLOCK.

1,160,466.

Specification of Letters Patent.

Patented Nov. 16, 1915.

Application filed November 9, 1914. Serial No. 871,032.

To all whom it may concern:

Be it known that I, WILLIAM H. THOMPSON, a citizen of the United States, residing at Memphis, county of Shelby, and State of Tennessee, have invented certain new and useful Improvements in Electric Automobile-Clocks, of which the following is a specification.

This invention relates to electric automobile clocks.

The present invention embodies improvements on the electric automobile clock set forth in my Patent No. 1,024,709, dated April 30, 1912 and in my application Serial No. 869,014, filed October 28, 1914, but it has the same general object in the provision of a clock intended for use on automobiles, locomotives, vessels and other vehicles where more or less constant vibration exists and where winding of a spring clock would be neglected except at irregular intervals with resulting deterioration and inaccuracy in keeping time. Automobile clocks are peculiarly subject to neglect and this, with the excessive vibration, soon impairs their reliability as time keepers.

As in the clocks of my application and patent aforesaid, the present invention employs spring driving means for the train and contact controlled electro-magnetically operated self-winding means embodying, in part, a maintaining spring for driving the train when the main spring barrel is being electro-magnetically wound.

The complete clock of the present invention embodies certain features found in the clock of my application Serial No. 869,014, filed October 28, 1914, but it has for its object the provision of improvements in the self-winding mechanism of that application and of my Patent No. 1,024,709; further, in the provision of a self-contained electric clock movement and an electrical connector, whereby flexible connecting wires or cords are done away with; further in other features more fully appearing hereinafter.

That part of the present invention which relates to improvements in the winding mechanism minimizes friction and lash and insures greater regularity of the driving action and reliability of the maintaining action at the instant the main spring is being wound by the electro-magnetic action, whereby greater efficiency is obtained in the even-

ness of application of the spring driving power to the train at all times. In carrying out this feature of the invention, I provide a stationary staff, as distinguished from a rotary arbor, and on this stationary staff there is mounted the balance disk and main spring, the pinion quill, maintaining barrel and maintaining spring. In consequence of this construction, friction is minimized and evenness of the driving power insured even when the driving disk is kicked back to wind the main spring. As a further means for minimizing friction, I provide a combined torsional and expansion coil spring which constitutes the sole connection between the maintaining barrel and the pinion quill which drives the train, doing away with the leaf spring and pins employed for that purpose in my Patent No. 1,024,709. The end of the pinion quill is so connected and arranged in relation to the head of the maintaining barrel that the wear is taken by the end of the quill instead of by the head of the maintaining barrel, resulting in diminished friction, as will appear more fully hereinafter.

The balance disk for winding the main spring, being loosely mounted on the stationary staff, is adapted to freely whirl thereon during re-winding of the main spring without opposing the driving action imparted to the train by the maintaining spring and barrel at the moment of re-winding. In consequence, the driving action is substantially uniform at all times and the clock runs with great regularity.

In the present invention I provide an improved electrical connector between the clock case and the frame of the movement. This connector consists of a spring contact carried by the self-contained clock movement, and an improved contact on the clock case, whereby the act of inserting the clock movement in its case, automatically brings the parts of the contact together and, on the other hand, the entire clock movement may be bodily removed from the clock case, causing separation of the parts of the electrical contact without requiring the use of wires or conductor cords or detachable fastenings of any kind. This electrical connector is set forth and claimed in a divisional application, Serial No. 15,512, filed March 19, 1915.

In my application Serial No. 869,014, I

have set forth and claimed a self-contained clock movement with shock absorbing springs interposed between the movement frame and the clock case. That construction contemplates the utilization of the pressure of the dial against the spacer shell of the bezel to hold the bezel on its screw-threads and prevent loosening or chattering by the vibration to which a clock may be subject when on an automobile or other vehicle. This construction I have improved by the provision of removable or releasable stop devices, such as screws, on the case which normally do not engage the frame of the clock movement or resist its tendency to hold the bezel in position, but which will engage the frame of the movement when the bezel is removed so that the clock movement will be retained in the case even when the bezel is taken off, thus permitting the hands to be set without danger of the entire movement springing out of the case. On the other hand, these stop screws may be loosened and permit the entire movement to be taken out. These stop screws are set forth and claimed in my Patent No. 1,148,728, dated August 3, 1915.

A further improvement consists in the omission of the coil spring for retracting the armature and in an improved construction and arrangement of a flat spring carried by the armature which serves to nullify the action of residual magnetism on the armature and also to act as a retracting spring therefor.

The foregoing recital of objects, advantages and improvements embodied in the present invention is to be considered as illustrative, rather than restrictive, of the scope of the invention.

In the accompanying drawings: Figure 1 is a section through the glass, bezel and case, showing the operative parts of the clock; Fig. 2, a plan view looking toward the electro-magnet, when the movement is detached from the case; Fig. 3, a detail section showing the electrical connection; Fig. 4, a detail view showing the binding posts; Fig. 5, a detail elevation of the driving and winding mechanism, the parts of the movement being in section to show how the staff is made stationary; Fig. 6, a detail view looking toward the head of the winding barrel; Fig. 7, a similar view with the head removed, showing the main spring; Fig. 8, a detail section through the winding, driving and maintaining mechanisms; Fig. 9, a detail showing the double brace connection for the main spring; and Fig. 10, a detail of the parts of the maintaining mechanism when disassociated.

All of the operating parts are self-contained as a complete movement and winding mechanism which may be bodily inserted into the shell or case 1 or bodily removed

therefrom. The shell or case has a screw-threaded part 2 onto which the bezel 3 screws, and it may have a flange 4 provided with suitable screw-holes for fastening the complete clock to the dash of an automobile 70 or other object. The glass 5 is carried by the bezel and the latter also has a spacer shell 6.

The frame of the movement has a dial plate 7 and front and back plates 8 and 9, 75 the plates 8 and 9 being connected by pillars 10 and all parts of the train being carried thereby. A supplemental back plate 11 is also secured by continuations of the pillars and this plate 11 constitutes a support for 80 the electro-magnet 12, one of whose terminals 13 leads to a connector 14 which is insulated at 15 from plate 11 and to which insulated wire 16 is connected. The armature 17 is of a single stamping, as proposed 85 in my application Serial No. 869,014, said armature being pivoted at 18 and 19 in the plates 7 and 11. The cord 16 runs through an opening 20 in the pivotal part of the armature and thence to a contact whose 90 back piece 21 appears in Fig. 1. The contact is on the opposite side of the armature from the plate 21 and is electrically connected to the back plate 21, but both the contact and back-plate are insulated from the 95 armature 17. Further description of this contact is deemed unnecessary in view of the disclosures of my Patent No. 1,024,701 and application Serial No. 869,014. To break the residual magnetism which would 100 tend to hold the armature 17 to the poles of the electro-magnet and also to do away with the coiled retracting spring which I propose to use in connection with the armature in my application Serial No. 896,014, there is 105 secured at 22 to the armature, a flat or leaf spring 23 whose free end presses against the pole of the electro-magnet and normally holds the armature against a suitable back stop 24. The other terminal 25 of the electro-magnet is connected to a binding screw 26 (Fig. 3) which is insulated by washers 27 from the plate 11 and is carried thereby. A nut and washer 28 afford means for connecting the terminal 25 to the screw or post 110 26 whose end projects freely at 29 and is snugly embraced by the contracted end of a coil spring connector 30 so that said spring 30 is permanently carried by the screw 26, and when the entire movement is taken out 115 of the case 1, this electrical connector 30 is carried by the frame. A cup 31 of insulating material is contained within the case 1 and has a reduced end entering an opening 32 in the back of said case or shell. A contact screw 33 holds this cup in position, there being provided an insulating washer 34 through which the screw passes. Suitable nuts and washers 35 secure the screw 120 and parts together and afford means for the 130

connection of a current supplying wire. The shell 1 may have another binding post 36 for the other part of the circuit from which the current is derived.

5 As in my pending application Serial No. 869,014, I provide a plurality, preferably three, of pillars or supports 37 which are surrounded by coil springs 38 whose inner ends 39 are cramped and engaged with the 10 pillars to hold said springs in position, but at the same time permitting them to freely expand or contract on the pillars. These springs constitute shock absorbing devices which are adapted to press against the rear 15 of the case 1 and to thereby hold the entire frame of the movement outwardly so that the dial is held against the spacer shell 6. Stop screws 40 are threaded through the shell 1 in position so that their tips will be 20 slightly free of contact with the plate 11 when the parts are in normal condition, as shown in Fig. 1. When the bezel is unscrewed, the springs 38 would tend to throw the movement outwardly. This is prevented 25 by the engagement of the plate 11 with the stop screw 40. Consequently, the bezel and glass may be taken off to set the hands 41 without disturbing the arrangement of the parts, but if it is desired to remove the movement 30 for any purpose, the screws 40 can be backed out until clear of the plate 11, whereupon the entire movement may be taken out.

When properly entered in the shell, the 35 contact spring 30 will enter the concavity in the cup 31 and press against the head of the screw 33, thus potentially establishing the circuit. The circuit is completed when the balance and winding disks turn, through un- 40 winding, sufficient to establish electrical connection with the armature contact.

Referring to Figs. 5 and 8, 42 is a staff which has a screw-threaded end 43 which is screwed into the plate 11 at 44, the other end 45 of the staff being loosely received in the plate 8 at 45. This staff remains stationary at all times, the screw-threaded part 43 being sufficient to hold it firmly, and consequently the provision of threads or a nut 50 45 is unnecessary. The staff is provided with a fixed or rigid hub 46 having a hook 47. Loosely mounted on the staff is a balance disk 48 which has a concavity 49. Contained within the concavity 49 is the main 55 or driving spring 50, one of whose ends is engaged with the hook 47 and the other end being provided with a double brace 51 which has one end received in an opening 52 in the balance 48 and its other end received 60 in a slot 53 in the disk-like head 54 which is frictionally seated in the rabbeted portion 55 of the disk 48. The engagement of the spring 50 with the hook 47 affords a permanent hold for one end of the spring so that 65 the driving action of the spring is imparted,

through the brace 51, to the driving or balance disk 48. Secured to the balance disk 48 in any desired manner, as by a driving fit for instance, is a sleeve 56 which is loose on the staff 42. A winding disk 57 has a 70 driving fit or suitable connection with the sleeve 56 so that the disks 48 and 57 turn as a unit. These disks are also connected by a cylindrical contact 58 which may be of any suitable metal and need not necessarily be of 75 platinum for the reason that this is so arranged in relation to the contact which is carried by the armature lever and connected member 21 that there is a wearing or rubbing engagement of the contacts at the time 80 the circuit is made and, consequently, no amount of sparking will so corrode these contacts that there will be any interference with the operation. The contact 58 also serves to connect the disks 48 and 57 and to 85 brace them one from the other. Loosely mounted on the staff 42 is a pinion 59 having an integral quill 60 which has a reduced end 61. The pinion 59 is engaged with the center wheel of the clock train and is the 90 means by which the spring power is communicated to said train. Loosely mounted on the quill 60 is a maintaining barrel 62 which has exterior ratchet teeth 63 adapted to be engaged by any suitable pawl 64 carried by the plate 8, such pawl and ratchet teeth holding the maintaining barrel against back action. Loosely received in the maintaining barrel is a disk-shaped head 65 which has a center hole 66 that has a tight 95 driving fit with the reduced part 61 of the quill 60 so that the disk 65, quill 60 and pinion 59 turn as a unit. The tip of the quill 60 extends beyond the disk 65 as at 67, and bears against the end of the sleeve 56, whereby the disk 65 is slightly spaced from the winding disk 57 and friction is minimized. The pinion quill 60 being of steel, the end 100 thereof bears against the end of the brass sleeve 56 which, also, reduces the friction and wear. Coiled around the quill 60 is a maintaining spring 68 which is both an expansion and a torsion spring and its function is two-fold. The spring has bent ends 105 69 and 70, the former of which is received in a notch 71 in the periphery of disk 65 and the latter in a hole 72 in the maintaining barrel. The spring 68, by its lengthwise expansion, acts against the disk 65 as an abutment (said disk being fixed to the end 61) and against the bottom of the maintaining 110 barrel 62 and presses the barrel against the pinion 59 which has a relatively small superficial area. Consequently, the barrel 62 is always kept out of contact with the winding disk 57 and thereby further reduce friction. The spring 68 is also a torsion spring, its tendency being to exert a driving action 115 on the head 65, and through it, to the pinion 59 and thence to the train. The retain- 120 125 130 135

ing pawl 64 serves to hold the maintaining barrel 62, and as the spring 68 is normally under torsional tension, it has this driving tendency.

Carried by the disk 57 is a suitable pawl 73 (Fig. 5) which always bears on the teeth 63 of the maintaining barrel 62, and it is through this pawl that the driving action of the spring 50 is transmitted to the barrel 62 and thence from said barrel by the interposition of spring 68, to the disk 65 and to the pinion quill and pinion 59, thus driving the train. Assuming that the spring 50 is under tension and the contact 58 is out of engagement with the armature contact, the aforesaid driving action is imparted to the train. When the contact 58 engages the armature contact, the circuit through the electro-magnet 12 is completed, whereupon the armature 17 is attracted with a snap-like action and the engagement of the armature contact with contact 58 results in an instantaneous whirl or twirl being given to the balance disk 48 and the winding disk, thus winding the spring 50.

As explained in my Patent No. 1,024,709 and application Serial No. 869,014, this electro-magnetic winding action would, if compensating means be not employed, tend to take the driving action off the train or to so reduce it that the beat and correct operation of the train would be seriously interfered with and the movement would keep poor time. It is, therefore, necessary to maintain the driving action on the train during each period of re-winding, although such re-winding is accomplished instantaneously. The maintaining mechanism of Fig. 10 accomplishes this object. During re-winding, the torsional action of spring 68 causes the pinion 59 to be driven for the brief period of such re-winding and thus the time keeping properties of the movement are not interfered with. It will be observed that the spring 68 has a capacity for a greater storage of driving power than the circular spring used for that purpose in my Patent No. 1,024,709, and I also do away with the provision of stops and pins by reason of the employment of the bent ends 69 and 70 and the openings 71 and 72. Furthermore, the mechanism is more easily assembled and taken apart and the spring has greater freedom of action than with the spring of said patent. It will be observed, however, that the spring 68 in addition to its maintaining function, also has the other function previously set forth of so correlating the parts that friction is minimized.

By the employment of the fixed staff 42 and the loose mounting of the disks 48 and 57 thereon, I not only obtain a compact arrangement, but the disk 48 serves as a balance disk, and in addition to that, the system is free to twirl on the staff 42 dur-

ing re-winding, without offering an opposing power to the maintaining power exerted by the spring 68 for, it will be observed, that during re-winding, the pawl 73 runs idly, around on the teeth 63.

Having thus described my invention, what I claim as new and desire to secure by Letters Patent, is:

1. In a clock, the combination with a stationary staff, of a spring-actuated driving barrel loosely mounted thereon, a pinion loosely mounted on said staff, a loosely mounted maintaining barrel, pawl and ratchet means for driving the maintaining barrel from the driving barrel, a maintaining spring constituting a driving connection between the maintaining barrel and the pinion, and a train driven by said pinion. 75

2. In a clock, the combination with a stationary staff, of a spring-actuated driving barrel loosely mounted thereon, a pinion and quill loosely mounted on said staff, a maintaining barrel loosely mounted on the quill, pawl and ratchet means for driving the maintaining barrel from the driving 80 barrel, a member loose in relation to the maintaining barrel and secured to the quill, and a combined lengthwise expansion and torsion spring surrounding the quill and engaged with said member and said maintaining barrel and adapted to constitute a driving connection between them and also to hold the maintaining barrel against the pinion, and a train driven by said pinion. 85

3. In a clock, the combination with a stationary staff, of a spring-actuated driving barrel loosely mounted thereon, a winding disk, a sleeve connecting the winding disk and spring driving barrel together whereby they are all adapted to turn on the stationary staff, a contact pillar connecting the spring barrel and the winding disk, an electro-magnet, an armature having a contact adapted to engage the contact pillar, a pinion, a maintaining barrel, a spring connecting the maintaining barrel and the pinion, pawl and ratchet means for driving the maintaining barrel from the winding disk, and a train driven by said pinion. 100

4. In a clock, the combination with a stationary staff, of a spring-actuated driving barrel loosely mounted thereon, a winding disk, a sleeve connecting the winding disk and spring driving barrel together whereby they are all adapted to turn on the stationary staff, a contact pillar connecting the spring barrel and the winding disk, an electro-magnet, an armature having a contact adapted to engage the contact pillar, a pinion and quill loose on said staff, a maintaining barrel loose on said quill, a member secured to the quill but disconnected from the maintaining barrel, a combined lengthwise expansion and torsion spring surrounding the quill and contained within the main- 110

- taining barrel, said spring having its ends engaged with said maintaining barrel and said member, and a train driven by said pinion.
5. In a clock, the combination with a driving wheel and main driving spring therefor, of a loose maintaining barrel adapted to be driven by the driving wheel, a pinion, a train driven by the pinion, and 10 a combined lengthwise expansion and torsion spring interposed between the pinion and the maintaining barrel and constituting a driving connection and maintaining power.
- 15 6. In a clock, the combination with a driving wheel and main spring therefor, of a loose maintaining barrel adapted to be
- driven by the driving wheel, a pinion and quill, said maintaining barrel being loose on the quill, the end of the quill constituting 20 an abutment bearing for the driving quill aforesaid, a member secured to the quill, a combined lengthwise expansion and torsion spring coiled around the quill within the maintaining barrel and having its ends engaged with the member and the maintaining barrel, and a train driven by said pinion.
- In testimony whereof, I hereunto affix my signature in presence of two witnesses.

WILLIAM H. THOMPSON.
